UNITED STATES PATENT OFFICE

FRANKLIN HARDINGE, OF CHICAGO, ILLINOIS, ASSIGNOR TO HARDINGE BROTHERS,
INCORPORATED, OF CHICAGO, ILLINOIS, A CORPORATION OF ILLINOIS

OIL BURNER

Application filed July 13, 1923. Serial No. 651,304.

My invention relates to improvements in oil burners, and is particularly concerned, though not necessarily limited, to oil burners of the rotary atomizer type.

5 The objects of my invention are:

First: To provide an oil burner comprising an atomizer, and means for supplying fuel thereto with automatic means for shutting off the supply of fuel to the atomizer in 10 the event the atomizer ceases to operate.

Second: To provide an oil burner comprising an atomizer, means for supplying fuel thereto, and means for igniting the combustible mixture formed by the atomizer, this 15 means being automatic in character.

Third: To provide a construction of the character described, including means for rendering the igniting means active for a predetermined interval of time and for then rendering the igniting means inactive.

Fourth: To provide means such as described in which the supply of oil to the atomizer and the control of the igniting means is effected through the movement of 20 a part of the burner.

Fifth: To provide an oil burner comprising an atomizing nozzle, means for supplying oil under pressure to the atomizing nozzle, means for igniting the combustible mixture 25 formed by the atomizer, and automatic means controlled by the pressure on the fuel supplied to the atomizer for determining the period over which said igniting means remains active.

Sixth: To provide an oil burner comprising an atomizing nozzle, means for supplying oil under pressure to said nozzle, a pilot light, and means controlled by the pressure on the oil supplied to said atomizer for automatically determining the period of time 35 during which the pilot light is operative for igniting the combustible mixture formed by the atomizing nozzle, and

Finally, to provide an apparatus of the 40 character described, which is simple in construction and economical to manufacture.

Other objects of my invention will appear as this description progresses, reference being had to the accompanying drawings, in 45 which—

Figure 1 is a side elevation, partially in elevation, showing certain details of construction of an oil burner embodying my invention;

Figure 2 is a plan view showing certain 55 details of construction of my improved burner, portions of the burner being broken away.

Figure 3 is a side elevation of the construction shown in Figure 2, portions thereof being broken away, and

Figure 4 is a transverse section taken on line 4—4 of Figures 2 and 3.

Throughout the several views, similar reference characters are used for referring to 60 similar parts, and the several sections are taken looking in the direction of the small arrows.

I have illustrated my invention as being embodied in an oil burner of the rotary 70 atomizer type, comprising a bed plate 10, and a base plate 11 mounted thereon. A hollow head 12 is carried by the inner end of the base plate and has journaled therein a rotary hollow spindle 13, on the upper end 75 of which is mounted an outwardly flaring atomizing nozzle 14, which projects through a suitable opening in the air ring 15 and is provided with fan plates or vents 16 for supplying air to the spray of oil which is discharged from the atomizing edge 17 of the atomizing nozzle.

The spindle 13 and the atomizing nozzle secured thereto are rotated by means of a suitable motor 18, which is connected through a 85 universal joint 19 with the shaft 20, the inner end of which is journaled in a suitable bearing in the head 12 and driving relation with the spindle 13 by means of any suitable gearing.

For supplying oil to the atomizing nozzle 14, I provide a suitable source of oil 21. A pump 22, preferably of the gear type, withdraws fuel from the tank 12 through the intake pipe 23, and discharges it through the pipe 24 into a pressure chamber formed by the pipe 25 and the four-way union 26. The pressure of the oil in the pressure tank just described is controlled by a pressure valve 27, which is connected with the upper end 100

of the pressure tank by means of the T-union 28 and the pipe 29. This pipe discharges into the supply tank 21. Oil flows from the pressure tank through a control valve 30 and a pipe 31 through the valve unit V, details of construction of which will later be described, and the pipe 32 into the lower end of a stand-pipe 33, which projects upwardly through the head 12, the hollow spindle 13, and discharges adjacent the bottom of the rotary atomizer 14.

10 The construction thus far described is more clearly set forth in my co-pending applications, Serial No. 572,455, filed July 3, 1922, and Serial No. 636,868, filed May 5, 1923, and further description thereof is believed to be unnecessary.

15 For igniting the combustible mixture formed by the atomizing nozzle, I provide one or more pilot lights 34, which project through the bottom 35 of the fire box of the furnace to which the oil burner is to supply heat. These pilot lights are supplied with gas through a pipe 36, leading from a suitable source of gas, the valve unit V, and the pipe 37.

20 From the above description, it will be seen that both the fuel supplied to the atomizing nozzle and the gas for igniting the combustible mixture formed by the atomizing nozzle, pass through the valve unit V. This valve unit comprises a body member 38 having a longitudinal bore 39 extending therethrough, which is somewhat reduced in diameter at the point where it intersects the transversely extending bore 40 passing through the valve body. The opposite ends of the bore 39 communicate with the pipes 36 and 37 respectively. A by-pass 41 extends 25 around the contracted portion of the bore 39, and may be provided with an adjustable needle valve 42, whereby the control of gas through the by-pass may be controlled as desired.

25 A plunger valve 42' is reciprocably mounted in the bore 40, and is provided at one end with an inwardly extending counterbore 43, which intersects the transversely extending bore 44 passing through the plunger valve 42'.

30 The valve body is provided with another transversely extending bore 45, which is parallel with the bore 40, and in which is slidably mounted a second plunger valve 46, having a longitudinally extending bore 47 which provides a passageway between the lateral ports 48 and 49. The valve body 48 is provided with two spaced ports 50 and 51, with which the ports 48 and 49 are adapted respectively to be brought into registry. The pipes 31 and 32 communicate with the ports 50 and 51 respectively, so that when the plunger valve 46 is in such position that the ports 48 and 49 register with the ports 50 and 51 respectively, oil can flow through the pipe

31, the valve unit V and the pipe 32 to the atomizing nozzle.

35 It is desirable to provide means for cutting off both the supply of oil to the burner and the main supply of gas to the pilot light 70 in the event the supply of electricity to the motor is cut off. For this reason, I provide means actuated by the motor for moving the two valves 42' and 46 to their open positions when the motor is running, and for moving these valves to their closed positions when the motor ceases to operate. This means is similar to that described and claimed in my co-pending application, Serial No. 636,868, filed May 5, 1923, referred to above, and in general comprises a collar 52 which is secured to the shaft 20, a pair of arms 53 having their outer ends pivotally secured to the collar 52, a second collar 54 which is slidably mounted upon the shaft 20 and pivotally connected 80 with the arms 53 by means of a pair of links 55. A tension spring 56 interposed between the two collars holds them in spaced relation, except when the shaft 20 is rotating, when the centrifugal force exerted upon the arms 53 and the links 55 cause them to swing outwardly, thereby moving the collar 54 toward the collar 52 against the tension of the spring 56. The collar 54 is provided with an annular groove 57 for receiving the roller 95 58, which is mounted upon one end of the bell crank lever 59. The bell crank lever 59 is pivoted at 60 upon a bracket 61, extending from one side of the valve body 38. The other end of the bell crank lever 59 is pivotally connected with the valves 42' and 46 by means of the pivot pin 62, so that movement of the lever 59 will be communicated to both valves. It will be noted that the outer end of the bell crank lever 59 is provided with an elongated slot 63 for receiving the upper reduced end of the pin 62. This slot permits rectilinear movement of the two valves 42' and 46.

100 From the above description, it will be apparent that when the motor is in operation, the two valves 42' and 46 will be urged to their open positions, but that when the motor ceases to operate these two valves will have been moved to their closed positions.

105 For igniting combustible mixtures formed from the heavier distillates and fuel oils, it is necessary to have a pilot light flame of considerable size and intensity, but after the combustible mixture has been ignited, there is no 110 reason for maintaining such a large flame, and I have therefore provided means for automatically reducing the flow of gas to the pilot light, after a predetermined interval of time subsequent to the starting of the oil 115 burner to the flow which is accommodated by the by-pass 41. For this purpose, I provide a pressure chamber 64, one end of which is closed by a flexible diaphragm 65 secured in place by means of the cap 66. This pres- 120

sure chamber is provided with an inlet pipe 67 which is connected with the pressure chamber formed by the pipe section 25 and the four-way union 26. This pipe ends in a boss 68, having a passageway 69 formed therein which communicates with the interior of the pressure chamber 64. A valve 70 may be provided for regulating the portage of this passageway for purpose which will later be referred to.

10 The pressure chamber 64 is provided with an outlet or discharge passageway 71 formed in the boss 72 and controlled by a valve 73. The passageway 71 communicates with the return pipe 74, the other end of which is connected with the return pipe 29, as shown in Figure 1. I provide an inwardly opening check valve 75 at the upper side of the pressure chamber 64. This check valve is held in its closed position by a very light compression spring. The pressure chamber 64 is supported upon one of the rails 77 of the burner by means of the bracket 78, which is secured to the rail 77 by a set screw 79.

25 As soon as the motor 18 begins to operate, the gear pump 22 starts pumping oil through the circulating system comprising the pipe 24, union 26, pipe 25, union 28 and pipe 29. Due to the presence of the pressure regulating valve 27, oil will be forced through the pipe 67 into the pressure chamber 64, from which it can return to the tank 21 through the pipes 74 and 29. By proper adjustment of the valves 70 and 73, the rate of discharge from the chamber 64 can be made smaller than the rate of supply thereto, and in this manner the pressure chamber 64 can be caused to fill in a predetermined interval of time. The check valve 75 will, of course, prevent the escape of oil from the pressure chamber through the port 80. As soon as the chamber 64 has become filled, the pressure of the oil therein will cause the flexible diaphragm 65 to bulge outwardly, thereby moving outwardly the link 81, which has its inner end pivotally connected with a boss 82 secured to the central portion of the diaphragm 65, and its outer end pivotally connected with a crank arm 83 secured to the upper end of the sleeve 84, which is mounted upon a stud 85 carried by the eccentrically mounted disc 86. This disc in turn is secured to the small base plate 87 and the rail 77 by means of a set screw 88 and a dowel pin 89. The connection between the link 81 and the crank arm 83 is formed by means of the pin 90 and the slot 91, to provide means for adjusting the throw of the crank arm 93 which is secured to and projects from the sleeve 84. The outer end of the crank arm 93 is seated in a transversely extending slot 94 formed in the outer end of the secondary plunger valve 95, which valve is slidably mounted in the bore 43 of the plunger valve 42.

65 After the motor 18 has once started, the

two valves 42' and 46 will be actuated by the centrifugal mechanism described above to permit a supply of oil to pass to the atomizer and a supply of gas to pass to the pilot light. The combustible mixture formed by the atomizer will consequently be ignited by the pilot light. Thereafter, the chamber 64 will gradually be filled, and when it has become filled, the pressure exerted upon the oil therein will cause the mechanism just described to move the plunger valve 95 inwardly to a position where its inner end will completely overlap and close the ports 44 extending transversely of the plunger valve 42', thereby cutting off the main supply of gas to the pilot

70

75

80

85

90

95

When, for any reason, the motor stops operating, the gear pump will likewise cease to operate, and there will be no further flow of oil to the chamber 64. The oil that is in this chamber will continue to drain therefrom through the pipe 74 until the pressure in the chamber is relieved to such an extent that the spring 96, confined between the cover 66 and the diaphragm 65, will return the link 81 to such a position that the plunger valve 95 will be retracted, so as not to prevent the flow of gas to the pilot light when the plunger valve 42' is again properly positioned by the centrifugal mechanism. The valve 75 and the port 80 are provided for the purpose of permitting the access of air to the chamber 64 during the drainage of oil from this chamber.

From the above description, it will be apparent that I have provided means for automatically controlling the supply of oil to the burner and the main supply of gas to the pilot light, and that I have also provided means for automatically cutting off the main supply of gas to the pilot light after it has been in operation for a sufficient period of time to positively insure the ignition of the combustible mixture formed by the atomizer. It will also be apparent that by adjusting the valves 70 and 73, the interval of time during which the main supply of gas can pass to the pilot light can be adjusted as desired.

While I have described the details of construction of the preferred embodiment of my invention, it is to be clearly understood that my invention is not limited to these details of construction, but is capable of other adaptations and modifications within the scope of the appended claims.

Having thus described my invention, what I claim is:

1. An oil burner comprising an atomizer, a pump for supplying oil to said atomizer, a motor for driving said pump, a pilot light for igniting the combustible mixture formed by said atomizer, means for supplying gas to said pilot light, including a valve comprising a body member having a port there-through, a valve member having a transverse

100

105

110

115

120

125

130

port to be brought into registry with the port in said valve body member, speed controlled means for actuating said valve member, said valve member having a bore intersecting the port therein, a plunger slidable in said bore, a pressure chamber connected with the pressure side of said pump, said pressure chamber having an outlet, means for adjusting the portage of said outlet, a dia-

5 phragm actuated by the pressure in said pressure chamber, and means actuated by said diaphragm for moving said plunger in said bore.

2. An oil burner comprising an atomizer, a

15 pump for supplying oil to said atomizer, a motor for driving said pump, a pilot light for igniting the combustible mixture formed by said atomizer, means for supplying gas to said pilot light, including a valve comprising a

20 body member having a port therein, a valve member having a port to be brought into registry with the port in said valve body member, speed controlled means for actuating said valve member, said valve member having a

25 bore intersecting the port therein, a plunger slidable in said bore, a pressure chamber connected with said pump, said pressure chamber having an outlet, and means actuated by the pressure in said pressure chamber for

30 moving said plunger in said bore.

3. An oil burner comprising an atomizer, a pump for supplying oil to said atomizer, a motor for driving said pump, a pilot light for igniting the spray formed by said atomizer,

35 means for supplying gas to said pilot light, including a valve comprising a body member having a port therein, a valve member for controlling the flow of gas through said port, speed controlled means for moving said valve

40 member to its open position, and means actuated through the operation of said pump for closing the port in said body member, and means for determining the time interval between the starting of said motor and the clos-

45 ing of said port.

4. An oil burner comprising an atomizer, a pump for supplying oil to said atomizer, a motor for driving said pump, a pilot light for igniting the spray formed by said atomizer,

50 means for supplying gas to said pilot light, including a valve comprising a body member having a port therein, a valve member for controlling the flow of gas through said port, means actuated by the pump motor for mov-

55 ing said valve member to its open position; and means actuated through the operation of said pump for closing the port in said body member.

60 5. An oil burner comprising an atomizer, a pump for supplying oil to said atomizer, a pilot light for igniting the oil spray formed by said atomizer; means for controlling the flow of gas to said pilot light, comprising a

65 valve, speed controlled means for opening

said valve, and means controlled by the operation of said pump for closing said valve.

6. An oil burner comprising an atomizer, a motor for actuating said atomizer, means for supplying oil to said atomizer, means for igniting the spray formed by said atomizer,

70 means actuated by said motor for activating said ignition means, and means actuated by the passage of oil from said supply means to said atomizer for rendering said igniting

75 means inoperative.

In witness whereof, I hereunto subscribe my name this 10th day of July, 1923.

FRANKLIN HARDINGE.
